UNITED STATES PATENT OFFICE.

LYMAN W. WELCH, OF GRAND RAPIDS, MICHIGAN.

REVOLVING-RACK SHOW CASE.

Application filed June 20, 1922. Serial No. 569,616.

To all whom it may concern:

Be it known that I, LYMAN W. WELCH, a citizen of the United States, residing at the city of Grand Rapids, county of Kent, State of Michigan, have invented certain new and useful Improvements in Revolving-Rack Show Cases of which the following is a specification.

This invention relates to improvements in revolving rack show cases.

The object of the invention is to provide an automatic closing means for the slot in the floor or base of such show case for accommodating the movable supporting column thereof.

Objects pertaining to details and economies of construction and operation will appear from the detailed description to follow.

I accomplish the objects of the invention by the devices and means described in the following specification. The invention is clearly defined and pointed out in the claims.

A structure which is a preferred embodiment of my invention is clearly illustrated in the accompanying drawing, forming a part of this application, in which:

Fig. I is a horizontal sectional view through a show case embodying the features of my invention, taken on a plane above the revolving rack of the show case.

Fig. II is an enlarged detail view of my improved automatic cover means for the slot, the column being shown in section and the base or floor being broken away at each side, the adjustment being indicated by dotted lines.

Fig. III is an enlarged detail sectional view through the slide means and the transverse sliding supporting column, taken on line 3—3 of Figs. I and II.

Fig. IV is an enlarged detail longitudinal sectional view taken on line 4—4 of Figs. I and II, showing details of the slide.

Fig. V is an enlarged detail sectional view taken on line 5—5 of Figs. II and III and VI, showing the connection of one of the side guideways to the floor of the rear pocket, and showing other details of construction.

Fig. VI is a detail plan view indicating the coupling of the side guideways to the floor of the rear pocket.

Fig. VII is a cross sectional view showing the structure of the slide at the point where

it is apertured to accommodate the movable column.

In the drawing similar numerals of reference refer to similar parts throughout the several views, and the sectional views are taken looking in the direction of the little arrows at the ends of the section lines.

Considering the numbered parts of the drawing by their numbers: 1 is the base of the show case; 2 is the rear wall; 3, 3 are the end walls; 4, 4 are the receding doors; 5 is the rack supported on the cross base arm 6, carried on the column 7 disposed in the aperture 8 of the slide in the transverse slot 9 in the floor 10 on the base 1. The receding revolving rack and case supported on the column are of a well known construction and are exemplified in my Patent No. 1,023,186, to which I refer for details.

Within the slot 9 I dispose the slide made up of adjustable sections 11 and 12, the section 12 being provided with upwardly projecting end stops 13. The sections 11 and 12 have an interlocking coupling 121 (see Fig. IV). These slides are supported on guideways 14, 14 at each side, the rear end of the slide 11 sliding into a pocket 15, having a floor 150 which is connected by key hole slot 151 to the guide 14 by the downwardly projecting key or button 141 having a head 142 to engage the said key hole slot 151.

The slide 11 is perforated at 8, as indicated, and is at that point provided with a bottom plate 110 which rides upon the guideways 14, a filler of veneer or fiber board 111 being placed between the bottom plate 110 and the top part 11 of the slide, to serve as a buffer to prevent noise.

The slide 11 is provided with little integral runners 112 which travel on the floor 150 of the pocket 15. Guard rails 17 are secured above the guideways by screws 19, 19, a floor 16 extending between the front ends of said guideways to cover the slot at that point. The cover 20 is disposed over the pocket 15 and is held in place by screws 21.

From this description it will be seen that when the rack with its column is swung to the front of the case (see Figs. I and II), it will pull the slide 11 out of the pocket 15 and cover the slot back of the column as it is withdrawn. The section 12 of the cover will slide upon the guides 14 above

the floor 16 until the front end contacts with the front wall of the case when the section 11 will disengage at the interlocking joint 121 and slide over the same, thus keeping the slot completely covered while the rack is being swung or pulled out. On the reverse movement the rear end of the section 11 of the slide will run into the pocket 15, the front portion will be withdrawn until it engages by the interlocking joint 121 with the section 12, when it will be withdrawn until the stops 13 engage the co-operating stops 18, which insures the complete opening of the slide and the stopping of the same at a predetermined point.

These parts, it is clear, are very readily and securely assembled by the arrangements that I have shown. All rattling is avoided by the means illustrated so that the cover 20 glides smoothly to place. I have described this structure in the form preferred by me, and I wish to claim that form specifically because of its merit, and I also desire to claim the invention broadly, as pointed out 25 in the appended claims.

Having thus described my invention, what I claim as new and desire to secure by Letters Patent is:

1. In a revolving receding rack show case structure, the combination of the floor with its slot and the rack with its supporting column movable in the said slot, of guideways at each side of said slot extending into a covered pocket at the rear and into a depressed portion at the front, detachable key hole slot joint between the said guideways and the floor of said rear pocket, a slide made up of sections with interlocking ends disposed in said ways, the rear one of which is perforated to embrace the said column, supporting contact shoe means for the rear section of said slide, stop means for the front section of said slide to insure its opening to cover the slot when the case is closed, and retaining strips above the said guideways notched to co-operate with the said stops at the front, as specified.

2. In a revolving receding rack show case structure the combination of the floor with its slot and the rack with its supporting column movable in the said slot, of guideways at each side of said slot extending into a covered pocket at the rear and into a depressed portion at the front, a slide made up of sections with interlocking ends disposed in said ways, the rear one of which is perforated to embrace the said column, sup-

porting contact shoe means for the rear section of said slide, stop means for the front section of said slide to insure its opening to cover the slot when the case is closed, and retaining strips above the said guideways notched to co-operate with the said stops at the front, as specified.

3. In a revolving receding rack show case structure the combination of the floor with its slot and the rack with its supporting column movable in the said slot, of guideways at each side of said slot extending into a covered pocket at the rear and into a depressed portion at the front, a slide made up of sections with interlocking ends disposed in said ways, the rear one of which is perforated to embrace the said column, stop means for the front section of said slide to insure its opening to cover the slot when the case is closed, and retaining strips above the said guideways notched to co-operate with the said stops at the front, as specified.

4. In a revolving receding rack show case structure the combination of the floor with its slot and the rack with its supporting column movable in the said slot, of guideways at each side of said slot extending into a covered pocket at the rear and into a depressed portion at the front, a slide made up of sections with interlocking ends disposed in said ways, the rear one of which is perforated to embrace the said column, and stop means for the front section of said slide to insure its opening to cover the slot when the case is closed, as specified.

5. In a revolving receding rack show case structure the combination of the floor with its slot and the rack with its supporting column movable in the said slot, of a slide made up of telescoping sections disposed to collapse at the front and cover the said slot when the case is open, and to open to cover the front of the slot when the case is closed, co-operating as specified.

6. In a structure of the class described, the combination comprising a rack with a supporting column disposed in a slot, of a telescoping slide adapted to collapse and expand to cover the slot in the front of said column.

In witness whereof, I have hereunto set my hand and seal.

LYMAN W. WELCH. [L. S.]
